UNITED STATES PATENT OFFICE

171,988

FOOD TONGS

Joseph Rossman, Passaic, N. J.

Application January 5, 1953, Serial No. 23,005

Term of patent 14 years

(Cl. D44—4)

To all whom it may concern:

Be it known that I, Joseph Rossman, a citizen of the United States, residing at Passaic, State of New Jersey, have invented a new, original, and ornamental Design for Food Tongs, of which the following is a specification, reference being had to the accompanying drawing forming a part hereof.

Fig. 1 is a side elevational view of a pair of food tongs showing my new design;

Fig. 2 is a top plan view thereof;

Fig. 3 is an end elevational view thereof;

Fig. 4 is a view in profile taken along line 4—4 of Fig. 1; and,

Fig. 5 is a view in profile taken along line 5—5 of Fig. 1.

I claim:

The ornamental design for food tongs, substantially as shown.
